VANITY CASE

**Theodore Sundin and Simon Morrison, New York,
N. Y., assignors to Vanstyle Specialties Corporation,
New York, N. Y., a corporation of New York**

Application March 24, 1937, Serial No. 132,775

10 Claims. (Cl. 132—82)

This invention relates to vanity cases such as are used by ladies in rouging and powdering their faces.

In the cosmetic trade, the expression "rouge" 5 is used to designate a highly colored cosmetic, which may be in powder form but usually is in the form of either paste or a dry cake. The ordinary make-up procedure involves, first, the application of rouge, and second, the application of a 10 slightly colored cosmetic. In the cosmetic trade, this slightly colored cosmetic is usually referred to merely as "powder," though it may be prepared either in cake or powder form. In specifically identifying "powder" prepared in a pulverized 15 condition, the cosmetic trade refers to it as "loose powder". The present invention is applicable to a vanity case adapted to carry both rouge and powder, but the invention is concerned primarily with a structure for carrying and dispensing the 20 powder in loose form. Thus the "powder" hereinafter referred to will be "powder" in the dictionary sense, and ordinarily it will also be "powder" in the cosmetic trade sense.

A general object of the invention is to provide 25 an improved vanity case structure for carrying loose powder and rendering it conveniently available to the user in appropriate quantities.

Another object of the invention is to provide a 30 vanity case which automatically applies powder to a powder puff in appropriate quantities.

A further object of the invention is to provide an improved vanity case structure suitable for quantity production and in which loose powder and a puff therefor may be conveniently carried 35 and kept readily available for use.

Still other objects of the invention are to provide a vanity case for loose powder, which is sufficiently powder tight; to provide a vanity case which can be readily refilled with loose powder 40 when the supply is exhausted; and to provide a vanity case which automatically keeps a powder puff appropriately supplied with powder as a result of the mere operations of opening and closing the case and removing and inserting the puff 45 therein.

Various additional specific objects of the invention will be apparent to those skilled in the art, from the disclosure herein.

Three specific forms of the invention are 50 closed, but all are of the same type. In each, the vanity case comprises two exterior generally cup-shaped shells, which are so pivoted together as to close in rim-to-rim contact in a conventional manner. In two of the forms disclosed there is 55 fitted into one of the shells a member adapted to

receive both a rouge cake and a puff for applying the rouge; and hinged to this inserted member is a mirror arranged to fold within the exterior case. In each of the forms disclosed, the other of the exterior shells is provided with a pivoted magazine assembly having a compartment for loose powder. A puff for the loose powder is carried in a puff compartment located beneath the powder magazine assembly; and the pivotal movement of the magazine permits easy insertion and 5 removal of this puff. Automatically operative means are provided to transfer appropriate quantities of powder from the powder compartment to the puff as the puff is inserted and removed.

Fig. I of the drawings is a plan view of one 10 form of the invention, showing the vanity case open and with some portions cut away to more clearly disclose certain features of the construction.

Fig. II is a section on an enlarged scale, taken 15 in general on the line II—II of Fig. I. In this figure also parts are shown as broken away to more clearly illustrate the structure.

Fig. III is a section, on an enlarged scale, taken 20 in general on the line III—III of Fig. I. For the sake of clearness, the powder puff is omitted from 25 this view.

Fig. IV is a detail plan view of a portion of that 30 exterior shell which carries the powder magazine assembly and the puff for loose powder.

Fig. V is an exploded isometric view showing the powder magazine assembly and a puff guide which is associated therewith. The cover for the powder compartment is shown removed; and to bring out certain features, it is shown in an inverted position.

Fig. VI is a fragmentary plan view of an open 35 vanity case, showing a second specific form of the powder magazine assembly. This form differs from the first form in the arrangement for closing the powder compartment.

Fig. VII is an elevational view, looking in the direction of the arrow in Fig. VI.

Fig. VIII is a plan view of an open vanity 40 case, showing a third form of powder magazine assembly.

Fig. IX is an enlarged sectional view, taken in 45 general on the line IX—IX of Fig. VIII.

Fig. X is an enlarged sectional view, taken in 50 general on the line X—X of Fig. VIII.

Fig. XI is a plan view of the main stamping for the powder magazine assembly of Figs. VIII, IX, and X.

In nearly all instances, it is necessary in drawing sheet metal articles to exaggerate the thick- 55

ness of the metal; and this should be borne in mind in connection with the accompanying drawings.

- Reference will first be had to Figs. I, II, and III.
- 5 Two generally cup-shaped sheet metal shells are designated as a whole by 1 and 2 respectively. These shells have flat bottoms, and have peripheral vertical flanges which are designated as a whole by 1^a and 2^a, respectively. By means of a
  - 10 pintle 3, the two shells are so hinged that they may be folded together with the vertical flanges 1^a and 2^a in edge-to-edge contact in a conventional manner to form the exterior of a vanity case.
  - 15 Positioned within shell 1 is a stamped sheet metal member 4, which provides a recess at 5 that may receive a rouge cake 6. Integral with the member 4 is a finger 4^a which projects horizontally above the rouge cake; and a rouge puff 7 may be slipped into the recess 5, beneath the finger 4^a. A mirror 8 is hinged at 9 to the inserted member 4, and this mirror may be made of steel or other suitable metal and be polished on both sides so that either side can be used as
  - 20 a mirror. Integral with the mirror 8 is a finger 8^a that is adapted to pass into and make snap engagement with rectangular aperture 10 to hold the mirror closed over the powder puff 7.
  - 25 In the shell 2 there is a powder magazine assembly, designated as a whole by 12; a puff guide, designated as a whole by 13; a powder puff 14; and a catch assembly designated as a whole by 15.

Referring more particularly to Fig. V, it will be seen that the powder magazine assembly is built up about a main sheet metal stamping 16 having a flat top portion 17, a well portion 18, and vertical side flanges 19 and 19' (see Fig. III). Well portion 18 is adapted to be closed by a removable closure 20 to form a compartment for loose powder. The closure 20 is formed with an annular depending rim 20^a and with a tongue 20^b which fits into a rectangular hole 18^a. Opposite tongue 20^b the closure 20 is provided with a projecting lip 20^c, which snaps into an elongated indentation 18^b in the main stamping 16. The applied position of the closure 20 is best illustrated in Fig. II. To facilitate removal, the closure 20 may be provided with a recessed portion 20^d, at which a purchase on the closure may be obtained (see Fig. I).

Stamping 16 is also formed with an end flange, designated as a whole by 21, and this flange is cut vertically from top to bottom, forming sections which are curled in the hinge members 21^a and 21^b (Figs. I and V). Similar hinge members are formed integral with the shells 1 and 2; and as indicated by Fig. I, the shells 1 and 2 and the stamping 16 are all hinged together on a common hinge pin. The portions of flange 21 which are left extending vertically after the formation of hinge portions 21^a and 21^b are arranged to be springy, and one or more of such vertical portions is adapted to engage the shell 2, as indicated in Fig. II, to resiliently elevate the powder magazine assembly 12 to the position shown in Fig. II. A felt strip 11 is preferably cemented or otherwise secured to flange 21 and arranged to prevent powder leakage through the slit portions of that flange and also to prevent powder leakage beneath the flange. Opposite to the hinged edge the powder magazine stamping 16 is formed with vertical portions 22 and 23, from which project horizontal stops 22^a and 23^a respectively, which will be referred to later. Between vertical portions 22 and 23, the metal is turned backwardly

toward the well 18, as shown at 24, (Figs. I and II); and at each side of the well 18 this metal which is turned backwardly may extend alongside of the well, as shown at 25 and 26.

The puff guide 13 is a single sheet metal stamping formed with horizontal side portions 30 and 31 between which is a dished portion 32. As shown in Fig. V, this stamping includes a vertical flange, designated as a whole by 33, which extends around three sides of the stamping. This flange is provided with holes h, two shown, which are adapted to make snap engagement with small projections p in the flange 2^a of the exterior shell 2.

Referring more particularly to Figs. II and IV, there is shown a catch assembly 15 consisting essentially of a push button 15^a, to which is fixed a conventional leaf spring 15^b that has a centrally located vertical projection formed into a catch 15^c. The flange 2^a of the exterior case 20 is provided with a rectangular hole through which the push button 15^a can be telescoped to position the leaf spring 15^b in the position shown in Fig. IV. Then the puff guide 13 is assembled into the shell 2 in the position shown in Figs. I and II, the holes h making snap engagement with the projections p. The vertical flange 33 of the puff guide is recessed, as shown at 33^a, to permit inward movement of the catch; and when pressure is applied to the button 15^a, the catch is moved inwardly against the pressure of leaf spring 15^b, the ends of which engage the dished portion 32 of the puff guide. Of course, when the vanity case is closed, the catch 15^c engages in a conventional manner with a suitable formation in shell 1 to hold the case closed.

The bottom of the powder well 18 is provided with a transverse slot 18^c (Fig. II), in which is mounted a powder transfer roller 36. Preferably this roller is so elongated as to extend nearly across the powder compartment; and preferably the surface of the roller is toothed or corrugated, as shown in the drawings, so that powder will be trapped between the teeth or corrugations. This roller 36 may be journaled in any suitable manner, as by shaft portions 36^a and 36^b which project through the side walls of the well 18. The holes which receive the shaft portions 36^a and 36^b may be somewhat larger than the shaft, as indicated in Fig. III to permit slight lateral movement of the roller.

It will be seen from Fig. II that the construction is such as to provide a puff compartment beneath the powder magazine assembly 12; and the puff 14 is normally carried in this puff compartment. When the vanity case is closed, the powder magazine assembly 12 is forced downwardly (in a clockwise direction viewed as in Fig. II), bringing the assembly more or less flush with the top of the flange 2^a of the shell 2. When the case is opened by pressing button 15^a, the spring action of flange 21 moves the powder magazine assembly upwardly (counterclockwise) until projections 22^a and 23^a strike the bottom of side portions 30 and 31 of the puff guide stamp. Thus, the powder magazine assembly is arrested in the position shown in Fig. II. The puff is withdrawn by pulling on loop 14^a, and as the puff moves outwardly, it causes transfer roller 36 to rotate and transfer powder from the powder compartment to the puff. Again, when the puff is returned to the puff compartment, the transfer roller 36 is rotated and more powder is transferred to the puff. Additionally, powder is transferred to the puff by rotation of the transfer

roller 36 which takes place during the upward and downward swinging of the powder magazine assembly 12 as the vanity case is opened and closed. By varying the length of the roller 36 and/or the size, depth and spacing of the teeth of the roller, the structure can be designed to transfer powder at any desirable rate.

The structure of Figs. VI and VII is the same as that of Figs. I to V, inclusive, except for the features relating to the closing of the powder compartment. In Figs. VI and VII, the main stamping for the powder magazine assembly is designated as a whole by 116, and the powder well is designated by 118. A closure 120 for the powder well is pivoted at R in any suitable manner to the stamping 116, the pivot preferably extending perpendicularly to transfer roller 36. Formed on the closure 120 is a depending annular rim 120^a which fits snugly into the well 118 when the powder compartment is closed. On the side opposite to pivotal connection R, the edge of the powder well is formed with indentations 118^b; and the closure 120 is formed with nose portions 120^c which snap into these indentations when the powder compartment is closed. To facilitate opening of the powder compartment, the closure 120 may be provided with a recessed portion 120^d, at which a purchase on the closure may be obtained.

Reference will now be had to Figs. VIII to XI, inclusive. Two conventional exterior shells designated as a whole by 201 and 202 respectively are hinged together at 203, and are arranged to be held closed together by a conventional catch assembly 215. Such exterior vanity case structure is conventional, and was described more fully in connection with the first form of the invention. A glass mirror M is shown secured in shell 201, but this shell may be equipped as per shell 1 in Fig. I, and vice versa.

Fitted into shell 202 is an annular sheet metal stamping, designated as a whole by 40. The metal of this stamping is so folded as to produce an outer peripheral flange 40^a which fits closely inside of the peripheral flange 202^a of the shell 202. Flange 40^a is suitably held in place by frictional engagement, or by snap engagement, with flange 202^a. Holding means similar to projections p and holes h (Figs. IV and V) may be used if desired. Integral with flange 40^a is an inner peripheral flange 40^b which merges into, and is integral with an inturned annular flange 40^c that rests against the bottom of shell 202.

A powder magazine assembly, designated as a whole by 212, is pivoted at V to the sides of frame 40. This assembly is built up about a main sheet metal stamping, which is designated as a whole by 216. Stamping 216 has a flat top portion 217, a well portion 218, and vertical side flanges 219 and 219' (See Fig. X). Well portion 218 is adapted to be closed by a pivoted closure 220, to form a compartment for loose powder. The closure 220 is stamped with an annular bead 220^a, and with an extension that is curled into a hinge portion 220^b. Opposite to the hinge portion 220^b, there is formed integral with the closure 220 a pair of snap-in fingers 220^c, 220^d. Stamping 217 is formed with a channel 42 which is arranged to receive hinge portion 220^b. A pin 43 extends through hinge portion 220^b and into the metal of stamping 216 to pivotally secure the closure 220 to the stamping 216. About the well 218 there is an annular rabbet formation 44 which receives the edge of closure 220, as shown in Fig. IX. Square holes 45, 45 receive the snap-in fin-

gers 220^c, 220^d to hold the closure 220 closed. A recessed portion 220^d, permits a purchase to be obtained on the closure 220 with a finger nail to open the powder compartment.

In the bottom of well 218, there is an opening 5 218^c, which receives a transfer roller 36 such as previously described. The shaft ends 36^a and 36^b of this roller are seated in bearing channels 46, 46 formed in stamping 216. Any suitable means may be used to hold the shaft ends 36^a and 36^b 10 in the channels 46, 46. One way is to extend the shafts through the metal of stamping 216, after the manner shown in Fig. III. Another way is to form the shafts with rounded ends, or conical ends, which are sprung into recesses formed in 15 stamping 216. A third way is by means overlying fingers struck from the stamping 216 adjacent to channels 46. As shown, the ends of shafts 36^a and 36^b are snapped under ridges 47, 47 formed in stamping 216. 20

Connecting side flanges 219 and 219' is an integral end flange 221, to which may be cemented (or otherwise secured) a felt sealing strip 211. The inner annular flange 40^b of frame 40 is vertically slotted adjacent to flange 221, to form a 25 spring tongue 40^b' which urges the powder magazine assembly 212 in a counter-clockwise direction (viewed as in Fig. IX). Bent from side flanges 219 and 219' are detents d, d which move in slots in flanges 40^b and arrest the powder magazine assembly in the position shown in Fig. IX. One of the slots is shown at 48 in Fig. IX. 30

In use, this form of the invention operates after the manner of the other two forms. A powder puff (not shown) is kept in the compartment below the powder compartment; and roller 36 transfers powder to the puff. Secured to, or integral with the frame 40 is a curved puff guide 213, which facilitates insertion and removal of the powder puff. 35

In compliance with the patent statutes, we have disclosed the best forms in which we have contemplated applying our invention, but it will be understood that the disclosure is illustrative and not limiting. 40

What is claimed is:

1. A vanity case comprising: a powder compartment; a puff compartment beneath the powder compartment; and a roller positioned between the compartments, part of the periphery 50 of the roller being within the powder compartment and part of the periphery of the roller being within the puff compartment, and the roller being operative to transfer powder from the powder compartment to the puff compartment. 55

2. A vanity case comprising: a rigid exterior case; a rigid powder magazine assembly pivotally mounted in the exterior case, said assembly having a compartment for loose powder; means to automatically elevate the magazine assembly 60 when the exterior case is opened; and a puff compartment below the powder compartment, the puff compartment and the powder compartment being in communication for the gradual passage of powder from the powder compartment to the 65 puff compartment.

3. A vanity case comprising: a rigid exterior case; a rigid powder magazine assembly pivotally mounted in the exterior case, said assembly having a compartment for loose powder; means 70 to automatically elevate the magazine assembly when the exterior case is opened; a puff compartment below the powder compartment, there being means to convey powder from the powder compartment to the puff compartment; and a 75

puff guide extending toward the puff compartment.

4. A vanity case comprising: an exterior shell; a frame fitted within said shell; a powder magazine assembly movably attached to said frame, the assembly having a powder compartment; a puff compartment beneath the powder compartment; and means to transfer powder from the powder compartment to a puff in the puff compartment.

5. A vanity case comprising: an exterior casing; a frame fitted within said casing; a powder magazine assembly pivotally attached to said frame, said assembly having a powder compartment; a puff compartment beneath the powder compartment; means to transfer powder from the powder compartment to a puff in the puff compartment; and means to automatically elevate the magazine assembly when the exterior casing is opened.

6. A vanity case comprising: an exterior casing; means within the casing forming a powder compartment and a puff compartment; and transfer means to transfer powder from the powder compartment to a puff inserted in the puff compartment, the transfer means being located to extend into the path of the puff and adapted to be actuated by insertion and removal of the puff.

7. A vanity case comprising: an exterior casing; means within the casing forming a powder

compartment and a puff compartment; and a transfer roller to transfer powder from the powder compartment to a puff inserted in the puff compartment, the transfer roller being located to extend into the path of the puff and adapted to be actuated by insertion and removal of the puff.

8. A vanity case comprising: an exterior casing; a rigid frame fitted within said casing; a rigid powder magazine assembly pivotally attached to said frame to permit a powder puff to be inserted beneath it; and a curved puff guide to facilitate insertion and removal of the puff.

9. A vanity case comprising: an exterior case structure; a powder magazine assembly within the exterior case structure, the assembly having a compartment for loose powder and being movable toward and away from the case structure, and there being a puff compartment between the powder compartment and the exterior case; and a powder transfer roller projecting from the powder compartment into the puff compartment for engagement and rotation by an inserted puff.

10. A vanity case as in claim 9, in which there is means to automatically move the powder magazine assembly away from the exterior case when the exterior case is opened.

THEODORE SUNDIN. 30
SIMON MORRISON.
